United States Patent Office

Des. 186,373

Patented Oct. 20, 1959

186,373

BUILDING BLOCK FOR FORMING ORNAMENTAL WALLS OR SIMILAR ARTICLES

Joseph Bedack and Charles Carotenuto, Jr.,
West Hollywood, Fla.

Application April 27, 1959, Serial No. 55,661

Term of patent 7 years

(Cl. D18—2)

Fig. 1.

Fig. 2.

Fig. 3.

Figure 1 is a perspective view of a building block for forming ornamental walls or similar articles showing our new design;

Figure 2 is a front elevation thereof; and

Figure 3 is an edge view thereof.

We claim:

The ornamental design for a building block for forming ornamental walls or similar articles, as shown.
